UNITED STATES PATENT OFFICE.

LOUIS A. LEHMANN, OF CORONA, NEW YORK.

DUMPING-BUCKET.

No. 891,940.

Specification of Letters Patent.

Patented June 30, 1908.

Application filed November 11, 1907. Serial No. 401,667.

To all whom it may concern:

Be it known that I, LOUIS A. LEHMANN, a citizen of the United States of America, and a resident of Corona, borough of Queens, city of New York, and State of New York, have invented certain new and useful Improvements in Dumping-Buckets, of which the following is a specification.

My invention refers to a dumping bucket used for various purposes such as, for instance, loading and unloading coal, gravel, earth, grain and other substances.

The object is to simplify, perfect and improve the mechanism whereby the bottom door or doors may be easily closed and held closed after the discharge of the contents of the bucket, and the invention consists essentially in a novel and ingenious arrangement of levers combined with the bucket and the door, and operating in such a manner that the door may be held tightly closed until the bucket is properly filled, and then by a manual or other operation of the lever-age mechanism the door may be easily opened and the contents discharged.

The invention also consists in numerous details and peculiarities in the construction, arrangement and combination of the various parts, substantially as will be hereinafter described and claimed.

In the accompanying drawing illustrating my invention: Figure 1 is a perspective view of my improved dumping bucket. Fig. 2 is a side elevation of the same, with the bottom door closed. Fig. 3 is a similar side elevation with the bottom door open.

Similar characters of reference denote like parts throughout the different figures of the drawing.

The body 1 of the bucket is made of any desired proportions and shape, being large or small, and is designed for use with any substance or material. The top is preferably open at 2, while the bottom is provided with a single door or cover 3, which is adapted to close the lower end of the bucket at times, and at other times to be removed from said lower end so as to allow the latter to be opened for the discharge of the contents of the bucket. This door 3 obviously constitutes the bottom of the bucket when closed, or, rather, when made to occupy the horizontal position indicated in Figs. 1 and 2. The bucket 1 may be provided with any

suitable bail, as 4, to which some suitable 55 hoisting rope or cable may be connected.

In the use of the bucket, it is very obvious that after it has been filled to the desired point, by shoveling into it through the upper end 2, the weight of the contents will rest 60 entirely upon the closed door 3, and consequently when said door is removed from below the lower end of the bucket, the contents will be emptied. The bottom door 3 is pivotally hung upon a horizontal shaft 5 which is securely fastened at the ends to the upwardly extending side bars 6 which lie alongside of the bucket, one on each side thereof, the upper ends of these side bars 6 being reversely bent at 7 to form a boxing 70 for a grooved pulley 8 which is arranged to roll on a short inclined track 9 securely fastened to the side of the bucket 1, there being one of these tracks on each side of said bucket. The tracks 9 are secured to the bucket by means of rivets 10, or other fastening devices, and the ends of these tracks are formed with projections 11 to limit the movement in each direction of the pulley 8. The boxing, containing the pulley 8, is provided with a pin 12 below the track 9, for the purpose of preventing the side bar 6 in its movement from being thrown upwardly so far that the pulley 8 would be dislodged from the track 9.

The two side bars 6 which carry the pulleys 8, as I have just described, may be rigidly fastened to the rod 5, on which the door 3 is hung, or said rod and the side bars 6 may be made integral with each other, constituting a single right-angled frame embracing the two sides and the bottom of the bucket; but this is a detail of construction or a modification in the precise form of the invention which may be adopted if preferred. The bottom door 3 is preferably strengthened by means of an angle piece 13 running around the edge thereof and securely fastened thereto. The pivoting of the door 3 upon the rod 5 may be accomplished in a variety of ways, 100 and I do not wish to be restricted to any particular means. One way is to provide the door 3 with bearings similar to journal boxes on the under side, through which the rod 5 passes. It is essential, however, that whatever means may be devised for this purpose the door 3 may be so hung on the rod 5 as to be capable of turning thereon, so that it may

pass from the position shown in Fig. 2, into the position shown in Fig. 3. Furthermore, the pivoting of the rod 5 to the door 3 is off the center line of the door 3 a short distance, so that the door is thereby divided into two parts, one of which 3^a, being wider than the other 3^b, is heavier, this arrangement being for the purpose of causing the door to drop into the vertical position shown in Fig. 3. After it is released from its horizontal position at the time the lateral bars 6 recede from the position shown in Fig. 2 into the position shown in Fig. 3, simultaneously dropping the door 3 and shifting it to one side beyond the lower corner of the bucket, so that the heavier weight of the part 3^a may drop it into the vertical position as already stated. When the door is thus being shifted and the lateral bars 6 are moving horizontally, the rollers 8 on both sides of the bucket are traveling down the inclined track 9, which results in bodily carrying the door 3 to one side, and also dropping it slightly below the bottom edge of the bucket, this latter movement resulting from the inclination of the track 9.

14, 14 denote links, one at each side of the bucket 1, which are pivoted at 15 to the side bars 6 at points about midway of the length of said side bars 6. The other ends of the links 14 are pivotally connected at 16 to the ends of the shorter arms 17 of the angular or bell crank levers 18, whose longer arms 19 project downwardly and are connected together by means of the handle rod 20. The bell crank levers 18 are pivoted at their angular points to the opposite sides of the bucket 1 by means of suitable pivoting means 21. By lifting the handle rod 20 the bell crank levers 18 are rotated upon their pivots 21, the consequence of which is that the links 14 are actuated and in turn they impart motion to the side bars 6 which carry the door 3.

In Fig. 2 the door 3 is shown as closed, and in Fig. 3 as open. The various levers which I have described composing the leverage mechanism for actuating the door 3 are in Fig. 2 represented in one position, and in Fig. 3 in another position. When the door 3 is closed the handle bar 20 is down alongside one of the faces of the bucket, and it will remain in this position until lifted, because the bell crank levers 18 are at this time situated with their long arms 19 substantially vertical, and their short arms 17 substantially horizontal, so that the links 14 are locked in the position where they hold the side bars 6 and the supported door 3 in an immovable position. In order to guard against any possibility of movement of the handle bar 20 at this time, which might prematurely open the door 3, which movement of the handle bar 20 might occur through undue jarring of

the bucket, or the handle bar 20 being caught by some entangling piece of mechanism, I hinge to the side of the bucket at 22 a short arm 23 which may be caused to project over the handle bar 20 and prevent it from rising. Assuming that the bucket is filled with material which it is desired to discharge, the process of opening the door 3 consists of disengaging the handle 20 from the retaining bar 23 and lifting it into the position shown in Fig. 3, the result of which act throws the bell cranks 18 around upon their pivots 21, reversing the position of the short arms 17 and consequently throwing the links 14 in a backward direction, which will actuate the side bars 6, which will be likewise moved backward, carrying with them the door 3 which at the same time drops enough to enable it to clear the bottom of the bucket. In this way the bottom 3 is removed from the lower end of the bucket and the contents thereof allowed to be discharged.

I do not wish to be confined to the idea of pivotally connecting the lower ends of the side bars 6 and the rod 5 to the door 3 at a point off the center, for although this may be a preferable method of pivotally supporting the bottom for the purpose hereinbefore specified, yet I am at liberty, when it is desired, to locate the rod 5 centrally across the bottom of the door 3, and when this center pivoting is employed it will be found in practice that the weight on the door 3 at the time of its opening will be sufficient to cause it to drop into the vertical position indicated in Fig. 3. Further, instead of manually lifting the handle bar 20 when the bucket is to be discharged, some mechanical device may be rigged for the same purpose, but this mechanical device may partake of a wide variety of forms; and also I wish it to be distinctly understood that the pivoting of the door to the rod 5 and the bars 6 may be changed materially in the details so long as the pivoting idea remains.

It is important, to obtain the best results, that when the handle bar 20 is dropped into its locking position, as shown in Fig. 1, the link 14 should be below the pivot pin 21 of the angular lever 18. This link 14 as we have seen is pivoted at one end to the side bar 6 and at the other end to the short leg 17 of the angular lever 18. When the angular lever 18 is caused to occupy the position shown in Figs. 1 and 2, the short leg or lever 17 thereof, to which the link 14 is pivoted, is placed in such a position that this link 14 is, as I have just said, below the pivot 21. Consequently with the bottom 3 now closed, the additional weight on said bottom caused by the filling in of the load of material will pull downwardly on the side bars 6 which will cause a downward pull on the links 14; but, as these are pivoted to the short legs 17

of the angular levers 18, the pull on these angular levers will be below their pivot pins 21, and the effect of such a pull will only be to cause the handle bar 20 to move tightly bind against the side of the bucket, as in Fig. 1, and hence there will be no possibility of opening the bottom of the bucket on account of the weight of material therein. In case the arrangement of the parts of the leverage were such that the links 14 were above the pivot pin 21, this effect would not follow, and there would be a tendency to pull the angular levers over into the position, or towards the position, shown in Fig. 3, and cause an opening of the bottom of the bucket, which could only be prevented by suitable means to hold the handle bar 20 down in its position against the side of the bucket. Although there may be cases where the links 14 might be placed above the pivot pins, yet it is one of the leading features of my present invention to have them located below the pivot pins when the bottom door is closed.

25 Many changes in the precise construction, combination and arrangement of the various parts may be made without exceeding the scope of the invention.

Having thus described my invention, what I claim as new and desire to secure by Letters Patent, is:—

1. In a dumping bucket, the combination with a bucket, of a door; and means for pivotally supporting the same, said means operating to open the door by shifting it to one side and slightly dropping it below the bucket, and said means including an inclined track along which the supporting mechanism is adapted to travel.

40 2. In a dumping bucket, the combination with a bucket, of a door therefor, lateral means pivotally connected to the bucket, said means being movably hung on inclined surfaces at the sides of the bucket and operating to shift the door and drop it sufficiently far below the bucket to permit its opening on its pivotal support.

3. In a dumping bucket, the combination with a bucket and a door therefor, of means carrying said door to which means the door is pivotally connected, lateral rails on the bucket on which move rollers forming a part of the door supporting means, and a leverage mechanism which controls the opening and closing of the door.

4. The combination with the bucket and

its door, of side bars pivotally supporting the door, rollers carried by said side bars, and inclined tracks for the rollers, all substantially as described.

60

5. The combination with a bucket and its door, of lateral side bars pivotally supporting the door, inclined tracks on the sides of the bucket along which tracks the side bars are movable, links pivoted to the side bars, pivoted bell crank levers pivoted to the opposite ends of the links, and means for operating the bell crank levers in opening and closing the door.

6. The combination of a bucket, a door at the bottom thereof, lateral bars pivotally supporting the door, inclined rails on which the side bars are movable, and a leverage mechanism for actuating the side bars, together with means for operating said leverage mechanism.

7. The combination of a dumping bucket, a door at the bottom thereof, a rod on which the door is movably hung, lateral side bars carrying said rod, inclined rails on which the side bars hang and move, links pivoted to the side bars, and levers for operating the links.

8. In a dumping bucket, the combination with the bucket, of a door at the bottom thereof, lateral means pivotally connected to said door at a point off the center line, inclines on which the side bars are movably supported, and means for controlling the action of the side bars in opening and closing the door.

9. In a dumping bucket, the combination with a bucket and a door, of means pivotally supporting said door; inclines on which said means is movably supported so as to travel bodily along said inclines, and a leverage for actuating the aforesaid means.

10. In a dumping bucket, the combination with a bucket and a door, of means for supporting said door, inclines on the side of the bucket on which the supporting means are hung and bodily travel, and a leverage for actuating said means, said leverage including links located below the pivotal points of the leverage to provide a locking effect when the door is closed.

Signed at New York city, this 7th day of November, 1907.

LOUIS A. LEHMANN.
